UNITED STATES PATENT OFFICE.

HERBERT HOFFMANN, OF RENVILLE, MINNESOTA.

GRAIN ELEVATOR.

Application filed December 14, 1925. Serial No. 75,256.

The present invention relates to a grain elevator.

An object of the present invention is to make an improved and simplified grain elevator of the chain conveyor type.

In order to attain this object, there is provided, in accordance with one feature of the invention, a charging bin having a sloping bottom with a discharge opening adjacent 10 the lowermost point thereof. In this opening is operatively mounted a helical screw for drawing the grain from the bin into an elevator where the grain is raised by means of a conveyor belt to a discharge opening at 15 the upper end of said elevator. The elevator is constructed in two readily separable sections, which may be disconnected and a lengthening section inserted between the elevator sections to increase the height to 20 which grain may be elevated by the device.

These and other features of the invention will be more fully brought out in the following description and accompanying drawings, wherein:

25 Figure 1, is a view in front elevation of a device made in accordance with the present invention, a portion of the elevating mechanism being broken away.

Figure 2, is a view in side elevation of 30 Figure 1.

Figure 3, is an enlarged sectional view on the line 3—3 of Figure 1.

Figure 4, is a view in side elevation of a lengthening device for the elevating mechanism.

Figure 5, is a view in front elevation of the device shown in Figure 4.

Figure 6, is a view in elevation of a side plate for the lower end of the elevating 40 mechanism.

Figure 7, is a sectional view on the line 7—7 of Figure 6; and

Figure 8, is a view in section on the line 8—8 of Figure 4.

45 Referring to the drawings in detail, a grain bin A comprises a frame 1 of angle iron having a sheet 2 of metal riveted thereto to form sides and a bottom for said bin. The inner end of the bin has a closure 3 of sheet metal riveted to the angle iron frame. The portion of the end below sheet 3 is closed by a cast metal plate 4 having an annular flange 5 extending outwardly therefrom around a discharge opening 6. A plate 8 is connected to the lower end of an

elevating mechanism B by means of bolts 7 extending entirely through said elevating mechanism and holding a second plate 9 on the opposite side thereof.

The plate 8 has an annular flange 10 extending outwardly therefrom about an opening 32 to receive the flange 5 which surrounds the discharge opening of the bin A. Extending around the sides and lower ends of the plates 8 and 9 are grooves 30 as illustrated in Figures 6 and 7. These grooves receive the edges of a sheet 31 of metal (see Figure 3), which forms a closure around the lower end of the elevating mechanism. The plate 8 is provided with a journal 11 centrally of the opening 32 to receive a shaft 12 therein. The outer end of the shaft is mounted in a journal 13 carried by supports 14 connected to the frame as by means of bolts 15. The plate 9, connected to the outer face of the elevating mechanism B, has a bearing opening 16 therein to receive the shaft 12. This construction forms a pivotal connection between the bin A and the elevating mechanism B and also provides a journal support for the shaft 12. Connected to the inner end of the shaft 12 as by means of brackets 33 is a helical screw 34 mounted in the opening 6 to rotate therein. Upon rotation of the shaft 12 the screw 34 is rotated 80 and draws grain from the bin A, through the opening 6, and into the elevator B.

Keyed to the shaft 12 to rotate therewith is a chain sprocket 25 with an elevator chain 26 mounted thereon. The elevator chain is 90 disposed in the housing to have one portion thereof above cross member 18 of an H-shaped housing (see Figure 8), the other portion of the chain being positioned below said cross member. The elevator chain 95 is provided with a plurality of flights 27 of a conventional type to raise grain in the elevator housing, when the chain is in motion, and discharge it through the discharge head. A second chain sprocket, not shown, 100 is pivotally mounted upon a shaft 36 in the discharge head C to support the chain 26 at its upper end. Upon the outer end of the shaft 12 are mounted a pair of pulleys 17 and 18', one of the pulleys being free to 105 rotate independently of the shaft 12; the other being keyed to the shaft to rotate therewith.

A housing for the elevator mechanism 110 comprises a central longitudinally extend-

ing member 18 which may be of wood, with a pair of side plates 19 and 20 connected thereto as by nailing. This forms a frame of H-shaped cross section, as shown in Figure 8, a closure 21 of sheet metal being provided across the upper face of the housing, and a similar closure member 22 across the lower face thereof. These closure strips may be connected to the side members as by nailing.

The upper end of the housing is provided with a pair of connecting plates 23 which extend outwardly from the sides thereof and are provided with holes therein to register with holes in plates 24 connected to a discharge head C. Bolts 35 are positioned in the holes in the plates to firmly connect the plates together and hold the parts in co-extensive position.

20 An extension section D comprises a portion of elevator housing similar to that illustrated in Figure 8, provided with connecting plates 28 at the upper and lower ends thereof. To elongate the elevating mechanism the discharge head C is removed, and the chain 26 is elongated by the insertion therein of a piece of chain of twice the length of the elongating section D. The elongating section is then inserted between 25 the main elevating mechanism B and the discharge head C, the connecting plates on the lower end of the elongating section being secured to the plates 23 and the upper plates

of the elongating section being secured to plates 24 of the discharge head.

By removing the discharge head from the elevator housing and reversing it from the position illustrated in Figure 1, it may be caused to discharge to the right instead of to the left. The elevating mechanism is pivoted upon the shaft 12 and upon the flanges 5 and 10 and may be pivotally moved about the shaft 12 as a pivot to a desired position.

What I claim is:

In an elevator of the character described, a frame, a charging bin mounted thereon having a flanged opening, an elevator housing having a flanged opening adapted to register with the flanged opening in the bin to form a pivotal connection between the bin and housing, a shaft journaled in said housing adjacent its upper end, a second shaft journaled in said housing adjacent the lower end thereof and having its ends extending beyond the walls of the housing, power means secured to the outer end of said second shaft, a screw conveyor mounted upon the inner end of the second shaft, and extending into the bin to afford means to move material from the bin to the housing, and an endless conveyor connecting the first and second named shafts whereby to elevate the material contained in the bin.

In testimony whereof I affix my signature.

HERBERT HOFFMANN.
